UNITED STATES PATENT OFFICE

BURT L. NEWKIRK, OF SCHENECTADY, NEW YORK, ASSIGNOR TO GENERAL ELECTRIC COMPANY, A CORPORATION OF NEW YORK

PROCESS AND APPARATUS FOR CLEANING LIQUID MERCURY AND THE LIKE

Application filed December 14, 1927. Serial No. 240,061.

My invention relates to the removal from a liquid, of foreign matter consisting of minute particles not wet by the liquid. By minute particles I mean particles so small that for the most part they cannot be resolved into separate particles by viewing through a microscope having a magnification of the order of two or three hundred diameters.

One situation where conditions requiring removal of such particles are met with, is in connection with the mercury vapor process for the generation of power. In this process, erosion of the metal surfaces sometimes occurs where a blast of mercury vapor, carrying globules of liquid mercury, strikes a metal surface. The metal so removed is steel or iron oxide in the form of minute particles of the order referred to above. They constitute a troublesome impurity in the liquid mercury which it is desirable to remove. In this connection, it is pointed out that such particles cannot be removed by mechanical filtering in the ordinary way because the particles are too fine, nor can they be separated out in a gravity separator or cleaner because they do not separate from the liquid mercury by gravity.

I have discovered that such minute particles have a tendency to form a skin or surface covering over an exposed mercury surface and that if such surface is brought into contact with a surface not wet by mercury liquid, such skin will be separated from the mercury liquid and will cling to the surface. The skin comprises liquid mercury covered more or less completely with the particles.

According to my invention, I develop a large mercury surface and bring such mercury surface into contact with surface of a material not wet by the mercury. By this means, the particles to be separated out cling to the surface of the material and hence are separated from the liquid mercury. The large mercury surface is developed by passing the mercury through a compartment or

a series of compartments filled with steel balls, gravel stones, wire screen, or similar bodies through which the mercury flows. In a compartment containing steel balls, for example, the balls are not wet by the mercury and consequently the mercury surrounds each ball with a skin of surface mercury, which skin is capable of holding particles of the foreign matter described above. I have found balls having a diameter of ⁵⁰ ⁵⁵ the order of $\frac{1}{8}$ " satisfactory.

It is known, of course, that a filter bed comprising steel balls, gravel stones or the like will serve as a mechanical separator or strainer for relatively large particles, it ⁶⁰ being known, for example, to filter water in this way. My invention comprises the discovery that a filter bed of the type described will remove from liquid mercury minute particles of a microscopic character. In this ⁶⁵ connection, it is to be noted that my separator does not operate as a mechanical separator in the ordinary sense, the particles to be separated out being so small that they could not be so separated.

In the drawing, Fig. 1 is a side elevation, partly in section of a structure embodying my invention, and Fig. 2 is a similar view of a modification.

Referring to the drawing, Fig. 1, 3 indicates a casing divided into compartments 4, 5, 6 and 7 by three partition walls 8, 9 and 10. In the upper portions of walls 8 and 10 are passages 11 and in the lower portion of wall 9 is a passage or passages ⁷⁵ 12. 13 indicates a conduit through which the liquid enters compartment 4 and 14 indicates a conduit through which the liquid flows from compartment 7. In the compartments are relatively small bodies 15 such as ⁸⁰ steel balls, gravel stones or the like. Such bodies float in mercury. To hold them down I provide a wire screen 16 located just below the plane of the lower edges of passages 11. 17 indicates the liquid in the separator. Its ⁸⁵ ⁹⁰ 90

level therein is defined by conduit 14 which extends to a point adjacent to the top of casing 3 and just above the plane of the upper edges of passages 11. By this means each of the chambers 4, 5, 6 and 7 is converted into a flotation chamber, the liquid being in each instance drawn off from the chamber at a point below the level of liquid in the chamber. The path of flow of the liquid through the chambers is indicated by the arrows.

In carrying out my invention, I may use only a single compartment. Preferably, however, I utilize a plurality of compartments connected in series as shown so as to provide flotation chambers for I have found that the material which collects on the surfaces of the separator may break away eventually and float to the surface of the liquid.

20 The modification shown in Fig. 2 is similar to that shown in Fig. 1 except that the balls or gravel stones have been replaced by woven screens 18 placed on edge.

What I claim as new and desire to secure by Letters Patent of the United States, is:

1. The method of separating from a liquid minute particles not wet by the liquid which comprises passing the liquid through a filter bed consisting of material not wet by the liquid and which serves to divide the liquid so as to develop a large liquid surface.

2. The method of separating from a liquid minute particles not wet by the liquid which comprises passing the liquid through a filter bed consisting of small bodies not wet by the liquid and which serves to divide the liquid so as to develop a large liquid surface.

3. The method of separating from liquid mercury minute particles not wet by mercury which comprises passing the liquid mercury through a filter bed consisting of small bodies not wet by the liquid and which serves to divide the liquid so as to develop a large liquid surface.

4. The method of separating from liquid mercury minute particles not wet by mercury which comprises passing the liquid mercury through a filter bed consisting of small bodies not wet by the liquid mercury.

5. Apparatus for cleaning liquid mercury consisting of a filter bed formed of small bodies not wet by liquid mercury and through which the mercury flows, and conduits for conveying liquid mercury to and from the filter bed.

6. Apparatus for cleaning liquid mercury consisting of a plurality of filter beds through which the liquid mercury flows in series, each filter bed being formed of small bodies not wet by liquid mercury, and conduits for conveying liquid mercury to and from the filter beds.

7. The method of separating minute particles from liquid mercury, which comprises passing liquid mercury through a filter bed

consisting of small bodies not wet by the liquid mercury and which serve to divide the liquid so as to develop a large liquid surface.

8. The method of separating minute particles from liquid mercury, which consists in dividing the liquid so as to develop a large liquid surface whereby the minute particles are brought to the surface of the liquid mercury.

In witness whereof, I have hereto set my hand this 13th day of December, 1927.

BURT L. NEWKIRK.
